UNITED STATES PATENT OFFICE

2,048,115

RAILWAY REFRIGERATOR CAR

Garth G. Gilpin, Riverside, Ill., assignor to Union Metal Products Company, Chicago, Ill., a corporation of Delaware

Application December 1, 1930, Serial No. 499,211

15 Claims. (Cl. 105—376)

The invention relates to refrigerator cars used by railways to transport perishable commodities, such as meat, milk, fruit and vegetables, which cars have their side walls, end walls, floors and 5 roofs insulated and are provided with an ice box or basket at one or both ends of the car. Hatchways are provided above the ice boxes for icing the ice box, which are closed by hatch plugs. The melting ice cools the interior of the 10 car and its contents by the cool air moving downwardly through an air space which surrounds the ice basket through an opening below the bulkhead, thence along the floor and, being warmed by the lading, rising to adjacent the ceiling and thence toward one of the ice baskets 15 through an opening over the bulkhead where it is cooled and repeats the movement. False floors are furnished to keep the lading slightly off the floor.

Such ice boxes are formed by providing an insulated partition or bulkhead, as it is called, about four feet from the end of the car, which bulkhead does not quite extend to the floor, nor to the roof or ceiling of the car, so as to permit the 25 movement of air heretofore described. A grained, latticed or open-work door of some kind may be hinged to the lower margin of the bulkhead to keep foreign matter out of the ice box and for cleaning the ice box. The space between the 30 upper margin of the door having a bulkhead and the ceiling of the car is partially closed by a grill or netting to also keep foreign matter out of the ice box.

As packages, boxes and barrels containing 35 heavy contents are frequently loaded in such refrigerator cars, these bulkheads must be very strong to resist the tendency of the cargo to shift, which tendency is caused by the sudden stopping or starting of the train. This inertia 40 force has been greatly increased in recent years by the use of heavy locomotives, long trains, hump yards and car retarders. The bulkhead is insulated so that the air cannot penetrate it and thus destroy the circulating movement hereto- 45 fore described. Such bulkhead, therefore, must be stiff enough to resist the inertia force of a shifting cargo so as not to destroy the insulation, but should have a certain amount of resiliency so that the blow of the shifting cargo will be 50 partially absorbed and not entirely transmitted to the side walls of the car which would have a tendency to destroy them and also destroy the insulating qualities of the car; furthermore, by providing means in the bulkhead to partially 55 absorb this shock the means which secure the bulkhead to the side walls may be materially reduced in strength.

It is customary to provide end walls for ordinary box or house cars which comprise a metal- 60 lic plate or plates provided with a plurality of

parallel contiguous corrugations which are preferably positioned horizontally and terminate within the plate or plates adjacent the opposite side walls of the car to which said plates are secured. Such a corrugated end wall has proved 5 to be very efficient in resisting shifting cargo and also in preserving the rectangularity of the entire superstructure of the car. Such an end wall may be lined or even insulated if desired.

One of the objects of this invention is to provide 10 a metallic bulkhead or partition which extends between the opposite side walls of the car and to adjacent floor and roof respectively of the car and comprises a metallic plate reinforced with a plurality of substantially horizontal corruga- 15 tions which preferably terminate within the plate adjacent the side walls of the car.

Another object is to form the substantially parallel corrugations so that one or more of them merge together adjacent the middle of the plate 20 to form a lesser number of stronger corrugations, thus providing a relatively stronger and stiffer plate adjacent the middle thereof and a relatively weaker and resilient plate adjacent the opposite ends thereof. 25

Another object of the invention is to insulate the corrugated bulkhead plates, which insulation and its protecting sheathing may be applied to the corrugated plate before it is installed in the car. A still further object is to provide the me- 30 tallic plate with flanges adjacent two or more of its margins which are arranged to protect the insulating means.

Another object of the invention is to provide 35 an insulated bulkhead which may be removed as a unit for repairs and replacements and to provide such insulated bulkhead with a foraminous door hinged to the upper margin thereof and preferably another foraminous door hinged to the lower margin thereof which doors may be par- 40 tially folded back to reduce the vertical height of the bulkhead so that it may be easily moved within the car while being removed from or replaced in the car. 45

Another object of the invention is to provide a 50 refrigerator car with a corrugated metallic end wall and a corrugated member or strut between the corrugated wall and the corrugated bulkhead so that they mutually reinforce each other.

Another object is to provide diagonal braces 55 which reinforce the bulkhead at its junctures with the side walls of the car, which preferably transmit stresses therefrom to the end sill and end plate respectively of the car.

Another object is to form the corrugations in the metallic bulkhead so that they occupy the space between the bulkhead and the ice basket and do not stop the circulation of the cooling air. 60

Another object is to provide a corrugated metal-

lic plate bulkhead which is formed and secured to the walls of the car so as to strengthen the car against lateral weaving, thereby preserving the superstructure of the car.

5 In the drawings:

Fig. 1 shows an interior view of a refrigerator car incorporating my invention looking toward the ice box or baskets of the car.

Fig. 2 is a section on line 2—2 of Fig. 1 showing 10 the relation of the end wall, bulkhead and ice box.

Fig. 3 is a section through the ice box of a refrigerator car incorporating my invention showing the ice grates and loading hatchways.

15 Fig. 4 is a horizontal section through the end wall partition, ice box and struts.

In the accompanying drawings the usual parts of the car are shown, such as side sill 2; side plate 3; side wall framing 4; side wall sheathing 5; side wall insulation 6; side wall lining 7; flooring 8; flooring insulation 9; upper flooring 10; roofing 12; roofing insulation 13; carlines 14; corrugated end wall 16; end wall sheathing 17; end insulation 18 and end lining 19.

25 The metallic plate bulkhead is provided with a plurality of substantially horizontal corrugations which preferably terminate within the metallic bulkhead adjacent the opposite margins thereof or adjacent the upright members 30 so 30 that any load imposed upon the corrugations is transmitted to the upright members 30 secured to the car (and preferably the post 32 which is braced by the member 34). These parallel corrugations preferably merge adjacent the middle 35 of the plate into a lesser number of preferably deeper corrugations, thereby obtaining a corrugated plate which is relatively stiffer and stronger adjacent its middle and relatively weaker and resilient adjacent the upright members which are 40 secured to the side walls of the car.

The end of the car is reinforced by a metallic plate provided with a plurality of substantially parallel corrugations which preferably merge together adjacent their middles to form a lesser 45 number of preferably deeper corrugations, which construction provides a relatively stiff and strong end wall adjacent its middle and a relatively weak and resilient end wall adjacent the side walls of the car to which it is secured. This end wall 50 is preferably insulated in the usual manner shown in Fig. 2.

The bulkhead or partition comprises a corrugated metallic plate 25 provided with flanges 26 and 27, which metallic plate is insulated by the 55 insulation 28 and sheathing 29, held in place by the wooden pieces 33 bolted to the corrugated metallic plate in the reentrant angles formed by the flat parts of the plate (adjacent the ends of the corrugations) and the flanges. The insulation 60 means and the flanges are substantially the same depth so as to provide protection for the edges of the insulation. By this arrangement the corrugated bulkhead may be insulated before the bulkhead is placed in position in the car. The 65 corrugations in the metallic plate project away from the insulation so that the insulation is backed up for substantially the length of the plate.

The bulkhead is removably secured to upright members 30 by means of bolts 31.

70 The ice box is located between the end wall and the bulkhead and comprises a series of ice grates 40 supported by a beam 41 adjacent the end wall of the car and by brackets 42 secured to the lower margin of the metallic plate forming 75 the bulkhead. Any convenient form of ice grates

may be used. The ice basket comprises a netting 44, adjacent to but spaced apart from the end wall, bulkhead and side walls, respectively.

The netting 44 forming part of the ice basket is spaced apart from the main body of the plate 25 forming the bulkhead and the reinforcing corrugations of the metallic plate are projected toward the netting and partially occupy the space 5 46 between the main body of the metallic plate bulkhead and the netting.

10 The corrugated end wall 16 and corrugated bulkhead 25 are made to mutually reinforce each other by the use of a strut 50 or a strut-tie positioned substantially horizontally and extending between the bulkhead 25 and the end wall 16 so as to transmit any horizontal thrust imposed upon one of said members to the other member; in other words, a thrust caused by a shifting cargo within the car against the bulkhead 25 is partially transmitted by the strut or 20 struts 50 to the corrugated end wall 16 and conversely a horizontal blow imposed upon the exterior of the end wall 16 is partially transmitted by the strut or struts 50 to the corrugated bulkhead 25. These struts are preferably positioned 25 opposite corrugations in the end wall and bulkhead, respectively, as shown in Fig. 2.

Nailing strips 51 are bolted to the end wall 16 within the corrugations, to which the end sheathing 17 is nailed, so that the bolt 52 does not extend through the sheathing. Framing members 54 are positioned in the space occupied by the end insulation 18 to back up the struts. The object of this, or a similar arrangement, is to keep the metallic strut out of engagement with the 35 end wall of the car so as not to form a conduit for heat into the ice box or refrigerated portion of the car.

The accompanying drawings illustrate the preferred form of the invention, though it is to be understood that the invention is not limited to the exact details of construction shown and described, as it is obvious that various modifications thereof, within the scope of the claims, will occur to persons skilled in the art.

I claim:

1. In a railway car having spaced apart side walls, the combination of a metallic end wall attached to the side walls and formed with a plurality of substantially horizontal corrugations, a bulkhead spaced apart from the end wall, said bulkhead comprising a metallic plate formed with a plurality of substantially horizontal corrugations, and a strut positioned adjacent the middle of the car and extending from the bulkhead to the end wall whereby they mutually reinforce each other.

2. In a railway car having spaced apart side walls, an end sill and end plate, the combination of a metallic end wall attached to the side walls and formed with a plurality of substantially horizontal corrugations, a bulkhead spaced apart from the end wall, said bulkhead comprising a metallic plate formed with a plurality of substantially horizontal corrugations, and braces 60 extending from adjacent the ends of the corrugations in the bulkhead to the corner posts of the car.

3. In a railway car having spaced apart side walls, an end sill and end plate, the combination of a metallic end wall attached to the side walls and formed with a plurality of substantially horizontal corrugations, a bulkhead spaced apart from the end wall, said bulkhead comprising a metallic plate formed with a plurality of sub- 70 75

stantially horizontal corrugations, a strut positioned adjacent the middle of the car and extending from the bulkhead to the end wall whereby they mutually reinforce each other, and braces 5 extending from adjacent the ends of the corrugations in the bulkhead to the corner posts of the car.

4. A bulkhead for a railway refrigerator car comprising a metallic plate, an insulation adjacent to said plate, said plate formed with a plurality of corrugations projecting away from said insulation which decrease in horizontal depth from their middles toward their opposite ends, and a netting forming part of an ice basket which 15 is spaced apart from said corrugations, whereby the area of the space for the descending cooling air is increased due to the decreasing in depth of the corrugations.

5. A bulkhead for a railway refrigerator car 20 comprising a metallic plate having a body portion and a flange at each side thereof, an insulation secured to said body portion, and a sheathing covering said insulation, said sheathing and insulation being solely secured to said bulkhead whereby the insulated bulkhead may be applied to the car as a unit, said body portion formed with a plurality of parallel corrugations which merge into opposite sides of the body portion adjacent said flanges.

30 6. A bulkhead for a railway refrigerator car comprising a metallic plate having a body portion and a flange at each side thereof, an insulation secured to said body portion, and a sheathing covering said insulation, said sheathing and insulation being solely secured to said bulkhead whereby the insulated bulkhead may be applied to the car as a unit, said body portion formed with a plurality of parallel corrugations projecting outwardly therefrom which 40 merge into opposite sides of the body portion adjacent said flanges.

7. A bulkhead for a railway refrigerator car comprising a metallic plate, an insulation adjacent to said plate, said plate formed with a plurality of corrugations projecting away from said insulation, the margins of the plate provided with flanges projecting in the opposite direction from the corrugations, said flanges being substantially the same depth as the thickness of the 50 insulation to provide a protection for the edges of the insulation.

8. In a railway car having spaced apart side walls, the combination of a metallic end wall attached to the side walls and formed with a plurality of substantially horizontal corrugations having a maximum depth adjacent the middle of the car, a bulkhead spaced apart from the end wall, said bulkhead comprising a metallic plate formed with a plurality of substantially horizontal corrugations having a maximum depth adjacent the middle of the car, and a strut positioned adjacent the middle of the car and extending from the bulkhead to the end wall whereby they mutually reinforce each other.

65 9. In a railway car having spaced apart side walls, the combination of a metallic end wall attached to the side walls and formed with a plurality of substantially horizontal corrugations, a bulkhead spaced apart from the end wall, said bulkhead comprising a metallic plate formed with a plurality of substantially horizontal corrugations,

rugations, means whereby said end wall and said bulkhead mutually reinforce each other against horizontal forces, and a strut positioned adjacent the middle of the car and extending from the bulkhead to the end wall whereby they mutually reinforce each other.

10. A bulkhead for a railway refrigerator car comprising a metallic plate having a body portion formed with a plurality of parallel corrugations merging into the opposite sides of the body portion to form flat marginal parts bent to form a flange projecting oppositely from the corrugations, wooden pieces secured to the metallic plate within the reentrant angle of said parts and said flanges, a sheathing secured to said pieces, 15 and an insulation between said sheathing and said plate.

11. A bulkhead for a railway refrigerator car comprising a metallic plate having a rectangular body portion formed with a plurality of parallel 20 corrugations merging into the opposite sides of the body portion to form flat marginal parts, said body portion provided with flanges on all four margins thereof projecting oppositely from the corrugations, wooden pieces secured to the metal- 25 lic plate within the reentrant angle of said parts and said flanges, a sheathing secured to said pieces, and an insulation between said sheathing and said plate.

12. In a railway car having spaced apart side 30 walls, the combination of a metallic end wall attached to the side walls and formed with a plurality of substantially horizontal corrugations, a bulkhead spaced apart from the end wall, and a strut between said end wall and said bulkhead 35 whereby horizontal thrusts imposed against the bulkhead are partially transmitted to the end wall.

13. A bulkhead for a railway refrigerator car comprising a metallic plate formed with a plu- 40 rality of parallel corrugations merging into the plate adjacent the ends thereof to provide flat parts between the ends of the corrugations and the ends of the plate, an insulation member positioned on the lading side of the bulkhead and 45 bearing against the plate between the corrugations and also against said flat parts whereby the insulation is backed up for substantially the length of the plate, and means to secure said insulation member to said plate.

50 14. A bulkhead for a railway refrigerator car comprising a metallic plate, an insulation mem-ber positioned on the lading side of the bulkhead and bearing against said plate, said plate formed with a plurality of corrugations merging into the 55 plate adjacent the ends thereof and projecting away from said insulation member whereby the insulation member is backed up by the portions of the metallic plate between the corrugations for substantially the length of the plate.

60 15. In a railway car having spaced apart side walls, the combination of a metallic end wall attached to the side walls and formed with a plurality of substantially parallel corrugations, a bulkhead spaced apart from the end wall, said 65 bulkhead comprising a metallic plate formed with a plurality of substantially parallel corrugations, and means whereby said end wall and said bulk-head mutually reinforce each other against horizontal forces.
